AUTOMATIC RECLOSED CIRCUIT BREAKER SYSTEM

Robert L. de Loache, Atlanta, Ga., assignor to Westinghouse Electric & Manufacturing Company, East Pittsburgh, Pa., a corporation of Pennsylvania

Application January 21, 1937, Serial No. 121,587

10 Claims. (Cl. 175—294)

My invention relates, generally, to circuit breaker systems, and, more particularly, to automatic reclosing circuit breaker systems.

The object of my invention, generally stated, is to provide an automatic reclosing circuit breaker system which comprises a simple control system using a minimum number of inexpensive relays and circuits which may be economically manufactured and installed and which shall be simple and effective in operation.

Another object of my invention is to provide an automatic reclosing circuit breaker system, which may be economically installed to operate circuit breakers already in use in the field by simple electrical and mechanical connections to such circuit breakers and without requiring any special apparatus to adapt the circuit breaker for use with the system.

A further object of my invention is to provide an automatic reclosing circuit breaker system which may be constructed of simple and inexpensive relays and switching devices which are well known in the art and are reliable in operation.

Another object of my invention is to provide an automatic reclosing circuit breaker system which shall function to instantaneously reclose a circuit breaker after it has been opened in response to an abnormal or predetermined condition on the line controlled by the circuit breaker, to automatically reclose the breaker at predetermined timed intervals in the event that the breaker trips on the first or any subsequent reclosure and to render the system ineffective to reclose the breaker at a predetermined time after the first opening in the event that the breaker continues to reopen upon being reclosed.

A still further object of my invention is to provide an automatic reclosing circuit breaker which will reclose instantaneously upon being opened in response to a predetermined condition on the line controlled by the breaker which will be closed at timed intervals and which will not be reclosed instantaneously in the event that it stays closed after an automatic reclosure until such predetermined time has elapsed from the last closure of the breaker.

A still further object of my invention is to provide an automatic reclosing circuit breaker system which shall function to reclose a circuit breaker a predetermined time after each opening of the breaker and to render the reclosing means inoperative to reclose the breaker at a time which shall depend upon the relative lengths of time that the breaker remains in the closed and open

position in any series of openings of the breaker in which the lengths of time between openings of the breaker are relatively close to the lengths of time between opening and reclosing of the breaker.

In practicing my invention in its preferred form, a control relay is provided for energizing the circuit breaker closing solenoid or other closing means in response to the opening operation of the breaker. The energizing circuit for the control relay includes the normally closed contact members of a timing relay which is energized and operated in response to the closure of the breaker and the control relay in order to de-energize the control relay. The timing relay is so constructed that it has a delayed reclosing action which delays the subsequent successive reclosures of the breaker for a predetermined time interval depending upon the setting of the relay. A time controlled relay, whose time delay is governed by the total time that the circuit breaker is open and the time that it remains closed, is provided for locking out the circuit breaker to prevent such a number of circuit breaker operations as might damage the breaker.

Additional objects of my invention will be pointed out in the following description of the same, taken in connection with the accompanying drawing, wherein—

Figure 1 is a diagrammatic view of an automatic reclosing circuit breaker system embodying the principal features of my invention, and

Fig. 2 is a diagrammatic view of a modification of the invention in which an automatic resetting means for the lock-out device is provided.

Referring to Fig. 1, a circuit breaker 10 is shown as connecting power source 11 with a load circuit 12. The circuit breaker 10 is normally biased to the open position by well known means, not shown in the drawing, and is held in the closed position by a latching device 17.

Means for tripping the breaker 10 is provided and is shown as a trip coil 13 which disengages the latch device 17 when energized by current from coil 14 which represents an overload responsive device on the load side of the breaker.

Circuit breaker 10 is closed by the usual closing coil shown as coil 15. The energization of coil 15 is controlled by contact members 16 which connect the coil with the control power source represented by lines X and Y through conductors 28, 29 and 30.

The control source referred to may be either alternating or direct current. When alternating current is used, the rectifier 44 is provided to

5

25

30

55

supply direct current to energize the closing coil 15. In the event that direct current is used, this rectifier may be eliminated and the coil 15 connected directly to conductors 28 and 29.

5 The circuit breaker 10 is provided with auxiliary contact members 31 which are closed when the breaker is in the closed position as shown, and auxiliary contact members 32 which are open when the breaker is closed. The function of 10 these contact members 31 and 32 will be described more in detail hereinafter.

In order to provide for timing the reclosing operations of the breaker a time delay relay 19, having contact members 20 and operating coil 15 33, is utilized. Element 21 is a diagrammatic showing of the retarding device for this relay which will retard the closing of contact members 20 for a predetermined time after the de-energization of coil 33; the opening of contact 20 members 20, however, is accomplished immediately upon energization of coil 33.

The time delay device 21 is shown as a dash pot in the drawing but may be any device, several of which are well known in the art, which 25 will perform the function of delaying the closing of contact members 20. An example of structure which might be used to accomplish the function of contact members 20 and its time delay device 21 is the time delay switch illustrated by the 30 patents to Rhodes 1,353,850, September 28, 1920, and 1,773,697, August 19, 1930.

A thermal current relay having normally closed contact members for controlling the energization of coil 18a of control relay 18 is provided and is 35 shown generally at 23. This relay in the preferred embodiment of the invention comprises a heating element 24, which, when energized, raises the temperature of bimetallic element 25 and when this temperature reaches a predetermined value, bimetallic element 25 flexes to open 40 contact members 26 and to engage behind the latch device, shown generally at 27, to lock contact members 26 open. The value of the current flowing through heating coil 24 may be adjusted by an adjustable rheostat 36 which is connected in series with heating element 24.

50 Means for maintaining the control relay coil 18a energized until the circuit breaker has been reclosed is provided in contact members 37 which are actuated to closed position when coil 18a is energized to form a holding circuit for coil 18a comprising conductor 38, contact members 31, conductors 39, 40 and 35, contact members 20, conductor 41, coil 18a, conductor 42, contact 55 members 26, bimetallic element 25 and conductor 34. This circuit is provided so that positive closure of circuit breaker 10 may be obtained before deenergization of its control relay 18.

The elements of the system are shown in their 60 normal positions with the circuit breaker in normal closed position.

In operation, when an overload or other fault, such as a ground or short circuit on the load circuit 65 12, causes the circuit breaker to trip open by means of overload coil 14 and trip device 13, a circuit for operating the control relay 18 is established by closure of contact members 32 which extends from supply conductor Y through conductor 43, contact members 32, conductor 35, 70 contact members 20, conductor 41, coil 18a, conductor 42, contact members 26, bimetallic element 25 and conductor 34 to the other supply conductor X. This energization of control relay coil 18a causes the closure of contact members 75 16 to energize the closing coil 15 of the breaker

through conductor 28, rectifier 44, closing coil 15, conductor 29, contact members 16 and conductor 30, thus causing an immediate reclosure of the circuit breaker 10.

When the circuit breaker 10 is actuated to its closed position, auxiliary contact members 32 are opened but the control relay 18 is held closed by a holding circuit comprising conductor 38, contact members 37, which were closed when relay 18 was energized by the opening of the breaker, 10 conductors 39, 40 and 35, contact members 20, conductor 41, coil 18a, conductor 42, contact member 26 bimetallic element 25 and conductor 34. This circuit is interrupted, however, at contact members 20 when the circuit breaker 10 reaches its closed position. At this time auxiliary contact members 31 are closed to energize the time-delay relay 19 through conductor 45, contact members 31, conductor 46, coil 33, conductor 47, conductor 29, contact members 16 and conductor 30.

When contact members 20 are opened, the energizing circuit of control relay 18 is interrupted and this causes the opening of contact members 16 and 31. The opening of contact members 16 25 deenergizes relay coil 33 and contact members 20 are closed after a period of time determined by the time delay setting of the device 21.

In the event that the fault or other cause for 30 overload on circuit 12 still exists when the circuit breaker is reclosed, overload coil 14 will again acutate trip device 13 to cause the breaker to open immediately upon reclosure. When the circuit breaker 10 again reopens, it will not immediately reclose for the reason that the circuit for the control relay 18 is held open at contact members 20 by the time delay device 21. After the period of time determined by the time 35 delay device 21 has elapsed, contact members 20 will close to energize coil 18 which will cause the closure of contact members 16 and thus energize the closing coil 15 of the circuit breaker. If after the second reclosure the fault still exists on the line, the circuit breaker will again 40 re-open and will again be reclosed after the predetermined time determined by the setting of the time delay device 21.

In order to limit the successive reclosures of the circuit breaker to a desired number such as 45 will prevent damage to the breaker, means is provided for locking the control circuit for the breaker in the inoperative position after a predetermined number of reclosures have occurred, if the circuit breaker immediately trips after each 50 reclosure.

This lock-out device comprises the thermal current relay 23 and its latching device 27. This relay is energized all the time that the circuit breaker 10 is open through conductor 43, contact members 32, conductor 35, conductor 40, adjustable resistance 36, conductor 48, heating element 24, contact members 26, bimetallic element 25 and conductor 34. The heating of the element 24 will be substantially continuous throughout the cycle of reclosures and reopenings of the circuit breaker, since the time that the circuit breaker stays closed under these conditions is very short.

The thermal current relay is set by adjustable resistance 36 so as to open contact members 26 70 after a time which is slightly greater than the product of the time delay period of the time delay relay 19 and the number of reclosures to which it is desired to limit the device after the first instantaneous reclosure, and shortly after this 75

number of reclosures has been made, if the circuit breaker again trips immediately, thermal current relay 24 will act to lock the circuit of control relay 18 open by movement of bimetallic element 25 to open contact members 26 and to latch them open by means of device 27.

As an example, if it is desired to have the circuit breaker close instantaneously and then reclose after a period of two minutes if it trips again immediately and then to lock out, the time delay device 21 of relay 18 will be set to allow the closure of contact members 19 after a period of two minutes and thermal current relay 23 will be adjusted by means of resistance 36 to open contact members 26 after a period of three minutes. Then if the circuit breaker trips, it will be reclosed immediately; if it trips again immediately it will be reclosed after two minutes; if it retrips again immediately thermal current relay 23 will have but one more minute to run before opening its contact members 26 to lock out the device and time delay device 21 will have two minutes to run before again closing contact members 20 to energize control relay 18. Thus, the control circuit will be locked out before the circuit breaker can be reclosed for a third time.

Obviously, the periods between reclosure and the number of reclosures may be adjusted as desired by adjusting the time delay of time delay device 21 and the time delay of thermal current relay 23. However, the first reclosure of the breaker will be instantaneous if the opening of the breaker occurs at a time after the last closure of the breaker which is greater than the time delay of the time delay device 21.

In order to set the system in operation again, it is necessary that the bimetallic element 25 be released from the latching device 27 to close contact members 26. This may be done by releasing the latch by hand.

In the modification shown in Fig. 2 of the drawing, there is shown a means for releasing the latch on bimetallic element 25 to close contact members 26 by operation of the control relay 18 and to energize relay 18 through an auxiliary manually controlled circuit when it is desired to set the system into operation again.

To accomplish this releasing operation, a crank 49 is provided on the latch member of latch device 27 and a shoulder 50 is provided on the contact member operating arm of control relay 18 so that the shoulder 50 will operate through the crank 49 to release the latch each time the relay 18 is energized. A push button switch 51 is provided to energize control relay 18 from the supply conductors X and Y. When it is desired to reset the device after it has been locked out by the latching of bimetallic element 25 by the latch device 27, push button 51 is closed to energize control relay 18, thus moving shoulder 50 to cause crank 49 to release the latch 27; at the same time contact members 16, shown in Fig. 1, are closed to energize the closing coil 15 of the circuit breaker 10. It will be noted that the latch device is tripped each time the control relay 18 is operated, but, of course, it will not be effective to affect the reclosing system until after the latch has operated to lock the system out.

It will be apparent from the foregoing description that I have provided an automatic reclosing circuit breaker system comprised entirely of simple and inexpensive relays and circuits therefor which will automatically reclose a circuit breaker instantaneously after it trips open and if it

continues to trip open, will automatically reclose the circuit breaker after an adjustable predetermined time interval and will limit the reclosures to an adjustable predetermined number, which system is simple, reliable in operation and easily installed either upon circuit breakers already in use in the field or as a part of the breakers as manufactured.

It is understood that the illustration and descriptions of the apparatus used are merely diagrammatic and equivalent structures may be substituted for those shown and described.

I claim as my invention:

1. In an automatic reclosing circuit breaker system, in combination, a circuit breaker, means for automatically opening the breaker in response to predetermined conditions, means for closing the breaker, a control relay having first and second contact members, said first contact members being in circuit with the breaker closing means, a first and a second auxiliary contact means, means whereby the first auxiliary contact means is closed when the circuit breaker is open and opened when the circuit breaker is closed, means whereby the second auxiliary contact means is opened when the circuit breaker is opened and closed when the circuit breaker is closed, an energizing circuit for the control relay which includes the first auxiliary contact means whereby the control relay functions to cause the circuit breaker to reclose substantially instantaneously after the first opening, a timing relay having normally-closed timed-reclosing contact members in circuit with the control relay coil and the first auxiliary contact means, a circuit for energizing the timing relay coil including the second auxiliary contact means and the first control relay contact members and an additional circuit including said second contact members of the control relay bridging said first auxiliary contact means when the control relay is energized, whereby the circuit breaker will be reclosed at intervals depending upon the time delay of the timing relay in the event that the circuit breaker reopens immediately after the first reclosure.

2. In an automatic reclosing circuit breaker system, in combination, a circuit breaker, means for automatically opening the breaker in response to predetermined conditions, means for closing the breaker, a control relay having first and second contact members, said first contact members being in circuit with the breaker closing means, a first and a second auxiliary contact means, means whereby the first auxiliary contact means is closed when the circuit breaker is open and opened when the circuit breaker is closed, means whereby the second auxiliary contact means is opened when the circuit breaker is opened and closed when the circuit breaker is closed, an energizing circuit for the control relay which includes the first auxiliary contact means whereby the control relay functions to cause the circuit breaker to reclose substantially instantaneously after the first opening, a timing relay having normally-closed timed-reclosing contact members in circuit with the control relay coil and the first auxiliary contact means, a circuit for energizing the timing relay including the second auxiliary contact means and the first control relay contact means, an additional circuit including said second control relay contact means bridging said first auxiliary contact means when the control relay is energized, whereby the circuit breaker will be reclosed at

intervals depending upon the time delay of the timing relay in the event that the circuit breaker reopens immediately after the first reclosure, and means in circuit with said first auxiliary contact means for rendering the reclosing system inoperative at a predetermined time after the first opening of the breaker in the event that the breaker will not stay reclosed.

3. In an automatic reclosing circuit breaker system, in combination, a circuit breaker, means for automatically opening the breaker in response to predetermined conditions, means for closing the breaker, a control relay having first and second contact members, said first contact members being connected in circuit with the breaker closing means, a first and a second auxiliary contact means, means whereby the first auxiliary contact means is closed when the circuit breaker is open and opened when the circuit breaker is closed, means whereby the second auxiliary contact means is opened when the circuit breaker is opened and closed when the circuit breaker is closed, an energizing circuit for the control relay which includes the first auxiliary contact means whereby the control relay functions to cause the circuit breaker to reclose substantially instantaneously after the first opening, a timing relay having normally-closed timed-reclosing contact members in circuit with the control relay coil and the first auxiliary contact means, an energizing circuit for the timing relay including the second auxiliary contact means and the first control relay contact members, and an additional circuit including said second control relay contact members bridging the first auxiliary contact means when the control relay is energized, whereby the circuit breaker will be reclosed at intervals depending upon the time delay of the timing relay in the event that the circuit breaker reopens immediately after the first reclosure, a thermal current relay controlled by the first auxiliary contact means for rendering the reclosing system inoperative at a predetermined time after the first opening of the breaker in the event that the breaker will not stay reclosed.

4. In an automatic reclosing circuit breaker system, in combination, a circuit breaker, means for opening the circuit breaker, means including a normally-closed delayed-reclosing relay and a control relay responsive thereto and operable in response to the opening of the breaker for effecting a substantially instantaneous reclosure of the circuit breaker, means including said normally-closed delayed-reclosing relay for effecting additional reclosures of the breaker at intervals determined by the reclosing delay of the delayed-reclosing relay in the event of an immediate reopening of the breaker after the first reclosure, and timing means responsive to the operation of the breaker for rendering the reclosing system inoperative at a predetermined time after the first opening of the breaker in the event that the breaker will not stay reclosed, said timing means for rendering the reclosing circuit inoperative comprising a relay having normally closed contact means and means for latching said contact means in open position, an auxiliary manually operated control circuit for energizing the control relay, and means operated by the control relay for tripping the latching means on each operation of the control relay.

5. In an automatic reclosing circuit breaker system, in combination, a circuit breaker, means for automatically opening the breaker, means

for closing the breaker, means responsive to the opening of the breaker for causing the breaker closing means to reclose the breaker substantially instantaneously, timing means for rendering the means which causes the circuit breaker closing means to close the breaker inoperative for a predetermined time after the timing means is actuated and means controlled by the circuit breaker whereby closure of the breaker actuates said timing means.

6. In an automatic reclosing circuit breaker system, in combination, a circuit breaker, means for automatically opening the breaker, means for closing the breaker, means responsive to the opening of the breaker for causing the breaker closing means to reclose the breaker substantially instantaneously, a first timing means for rendering the means which causes the circuit breaker closing means to close the breaker inoperative for a predetermined time after said first timing means is actuated, means controlled by the circuit breaker whereby closure of the breaker actuates said first timing means, a second timing means for rendering the reclosing system inoperative after a predetermined energization of said second timing means and means controlled by the circuit breaker for energizing said second timing means during the open circuit condition of the circuit breaker.

7. In an automatic reclosing circuit breaker system, circuit breaker closing means, circuit breaker opening means, normally open circuit control means, means for closing said normally open circuit control means when the circuit breaker opens, a timing relay having normally-closed delayed-reclosing contacts, means for actuating said circuit breaker closing means substantially instantaneously after the opening of the breaker including said normally-closed relay contacts and said normally open circuit control means and a control relay connected to energize said circuit breaker closing means, and means including said timing relay and said control relay for effecting additional reclosures of the circuit breaker at intervals determined by the interval of reclosing delay of the contacts of the timing relay in the event that the circuit breaker reopens after the first reclosure within the interval determined by the interval of reclosing delay of the contacts of the timing relay.

8. In an automatic reclosing circuit breaker system, a circuit breaker closing means, a circuit breaker opening means, a timing relay having normally-closed delayed-reclosing contacts, circuit control means controlled by said circuit breaker, a control relay for said circuit breaker closing means, means for effecting a substantially instantaneous reclosure of the circuit breaker in response to the opening of the breaker including said circuit control means, said control relay and the contacts of said timing relay, and means including said timing relay and said control relay for effecting additional reclosures of the breaker at intervals determined by the interval of reclosing delay of the contacts of the timing relay in the event of an immediate reopening of the breaker after the first reclosure.

9. In an automatic reclosing circuit breaker system, a circuit breaker closing means, a circuit breaker opening means, a timing relay having normally-closed delayed-reclosing contacts, circuit control means controlled by said circuit breaker, a control relay for said circuit breaker closing means, means for effecting a substantially instantaneous reclosure of the circuit breaker in

response to the opening of the breaker including said circuit control means, said control relay and the contacts of said timing relay, means including said timing relay for effecting additional reclosures of the breaker at intervals determined by the intervals of reclosing delay of the contacts of the timing relay in the event of an immediate reopening of the breaker after the first reclosure, and additional timing means responsive to said circuit control means for rendering the reclosing system inoperative at a predetermined time after the first opening of the circuit breaker in the event that the circuit breaker will not stay reclosed.

15 10. In combination, a power supply circuit, a

load circuit, a circuit breaker between the two circuits, means for opening the circuit breaker in response to predetermined abnormal conditions, control relay means responsive to the opening of the breaker for immediately reclosing the breaker, timing relay means responsive to said control relay means and the reclosure of the breaker for delaying subsequent reclosures of the breaker in the event that the breaker continues to reopen, and additional timing means responsive to the open condition of the breaker for preventing reclosure of the breaker after a predetermined number of reclosures in the event that the breaker continues to reopen. 5 10

ROBERT L. DE LOACHE. 15
